UNITED STATES PATENT OFFICE.

LOUISE D. STEWARD, OF BOISE, IDAHO.

ATTACHMENT FOR OVENS.

1,239,632.

Specification of Letters Patent. Patented Sept. 11, 1917.

Application filed January 22, 1915. Serial No. 3,753.

To all whom it may concern:

Be it known that I, LOUISE D. STEWARD, a citizen of the United States, residing at Boise, in the county of Ada and State of Idaho, have invented certain new and useful Improvements in Attachments for Ovens, of which the following is a specification.

My invention relates to new and useful improvements in attachments for ovens and is more particularly designed for use in connection with domestic ovens.

The object of the invention is to provide a movable shelf for the interior of the oven so that the articles contained thereon may be shifted to different parts of the oven to regulate the cooking thereof.

A further object is to provide means exterior of the oven for moving the shelf to various points within the oven to modify the oven space by increasing or decreasing the size of the heating space in which the article is being cooked, also for positioning the shelf adjacent the floor of the oven or near the roof thereof.

And a further object is to provide means for retaining the shelf in its adjusted position.

Other objects and advantages will be hereinafter more fully set forth and pointed out in the accompanying specification.

In the accompanying drawing which is made a part of this application,

Figure 1 is a vertical longitudinal sectional view through a kitchen range showing one form of the shelf and its attachment applied thereto;

Fig. 2 is a vertical transverse sectional view thereof as seen from line 2-2 of Fig. 1;

Fig. 3 is a similar view of a modified form;

Fig. 4 is a detail elevation partly in section, of one form of adjusting mechanism for the shelf, and

Fig. 5 is a detail plan view of the means employed for positively retaining the shelf in its adjusted position.

Referring to the drawings, in which similar reference numerals designate corresponding parts throughout the several views 1 denotes the range proper which may be constructed in any suitable manner, and 2 indicates the oven therein, the door 3 of the oven preferably having a bulged portion 4.

Rotatably mounted within the oven 2 and

extending through the rear wall of the oven and the rear wall of the range, is a shaft 5, said shaft being preferably positioned adjacent the upper portion of the oven and near the rear side wall thereof. Fixedly secured to the shaft 5 and adapted to rotate therewith are sprocket gears 6, one gear being placed adjacent the rear wall of the oven and one adjacent the front wall thereof, and co-operating with said sprocket gears are similar sprockets 7 which are rotatably mounted upon stub-shafts mounted in the front and rear walls of the oven and adjacent the edge of the oven having the door thereon, the sprockets 6 and 7 being connected with each other and caused to rotate in unison by means of sprocket chains 8 so that when the shaft 5 is rotated, the sprockets 7 will be simultaneously rotated with the sprockets 6. Fixed to the shaft 5 and in juxtaposition to the sprockets 6 are arms 9, while a similar pair of arms 10 are attached to the sprockets 7, the lower ends of said arms being pivotally secured to a shelf 11, said shelf being constructed in the usual or any preferred form and employed for supporting the articles being cooked.

As shown in Figs. 1 and 2, the arms 9 and 10 are of such length that the shelf 11, when in its lowered position, rests in a plane at a point substantially half the height of the oven, but as shown by dotted lines in Fig. 2, the shelf can be positioned adjacent the roof of the oven by rotating the shaft 5, and to facilitate the operation of the shafts and parts attached thereto, from the exterior of the oven, a crank 12 is attached to the projecting end of the shaft. The shelf 11 is held in its adjusted position through the medium of the spring-pressed latch 13 carried by the crank 12 and a suitable rack 14 attached to the rear wall of the range, the latch being so positioned that it will be released from the rack when the handle portion of the crank is grasped to operate the same, and when the shelf has been placed in proper position, the releasing of the handle of the crank will likewise release the latch so that it will again be moved into engagement with the rack bar and will hold the crank against further rotation.

By properly bulging the door 3, the shelf may be moved to its elevated position adjacent the roof of the oven without opening the door.

In the form shown in Fig. 3 of the draw-

ing, the sprockets 6 and 7 are dispensed with and the arms 9' and 10' are made of such length that when the shelf 11' is in its lowermost position, it will rest adjacent the floor 5 of the oven, the operation of the parts for elevating the shelf being similar to that shown in Figs. 1 and 2, except that the movements of the arms 10' are regulated by the movements of the arms 9' which latter 10 arms are fixed to the shaft 5'.

This form of construction is primarily adaptable for supporting and handling heavy articles, and as shown by dotted lines in Fig. 3, the articles may be moved to a 15 point where they can be removed from the shelf or placed thereon, as the lengths of the arms 9' and 10' are such as to dispose a portion of the shelf a distance beyond the opening in the oven.

20 In Fig. 4 of the drawing, the construction therein shown embodies both features of the device previously described in that the arms 15 are substantially of the same length as the arms 9 and 10, and coöperating therewith are hollow sleeves 16, the lower ends of which are pivoted to the shelf as in the other forms.

With this form of device, the sleeves may be telescoped with the arms 15 and the shelf 30 carried in the same relative position as the form shown in Fig. 2, or by lowering the sleeves their full distance, the shelf will be disposed in the same relative position as in Fig. 3, the sleeves being held in their adjusted positions on the arms in any suitable manner as by set screws 17. It will be understood, of course, that the sleeves 16 may be adjusted to any point upon the arms 15, thus disposing the shelf at any required 40 height within the oven.

By suspending the shelf in the manner shown, it will be readily seen that it can be quickly disposed out of operative position so that the full capacity of the oven can be used, or moved to increase or decrease the 45 heating space above or below the shelf, as occasion may require, and without opening the oven door.

In this manner the heat may be uniform throughout the oven or it may be increased 50 in parts thereof by manipulating the position of the shelf as set forth.

I claim:

1. In combination with an oven, a shaft journaled in the side walls of the oven near the top, a pair of normally depending arms secured to said shaft, a pair of stub shafts also journaled in the side walls of the oven near the top and each carrying a normally depending arm, a shelf pivotally secured to the lower ends of said pairs of arms, and means connected to the shaft to move the shaft and pairs of arms in unison and move the shelf vertically within the oven. 60

2. An attachment for ovens comprising the combination with a shelf, of a pair of arms pivotally mounted in the oven, and having their lower ends pivoted to the shelf, a second pair of arms pivoted in the oven and having their lower ends pivoted to the shelf, sprockets connected with said arms and sprocket chains coöperating with the sprockets to cause the second set of arms to move coincident to the first set of arms, and means whereby rotating movement may be 70 applied to the first set of arms. 75

3. An attachment for ovens comprising the combination with a shelf, of a shaft extending through the oven, a pair of sprockets fixed to said shaft, arms also fixed to 80 said shaft adjacent said sprockets, a second set of arms rotatably mounted on the walls of the oven, sprockets fixed to said arms, sprocket chains connecting said sprockets to cause the second mentioned arms to rotate 85 with the first mentioned arms, the ends of said arms being pivoted to the shelf, means whereby rotating motion may be imparted to said shaft, and means to hold the shaft against casual rotation. 90

In testimony whereof I affix my signature in presence of two witnesses.

LOUISE D. STEWARD.
